UNITED STATES PATENT OFFICE.

JAY KELLY LIVINGSTON, OF TULSA, OKLAHOMA.

CASING CATCHER.

Application filed November 17, 1922. Serial No. 601,532.

To all whom it may concern:

Be it known that I, JAY K. LIVINGSTON, a citizen of the United States, and a resident of Tulsa, in the county of Tulsa and State of Oklahoma, have invented certain new and useful Improvements in Casing Catchers, of which the following is a specification.

This invention relates to a casing catcher.

In drilling oil wells, or the like, the drilling proceeds as long as possible and then a string of casing is lowered. Usually the drilling can be continued until a water level is reached and the well at this time fills with water and drilling must be discontinued. A string of casing is then lowered, said string consisting in a number of casing sections threaded together and each string corresponding in length to the depth of the well. At each time a new water level is reached, a string of casing must be lowered which is equal in length to the depth of the well and adapted to fit within the preceding string of casing.

Also it may be mentioned that in case a well is not productive it is desirable to withdraw the strings of casing.

When lowering a string of casing it often occurs that the lowering means give away and the string of casing drops into the well. This necessitates an extensive fishing operation in order to remove the casing so that drilling may be continued. Sometimes it is impossible to remove the casing so lost and the well must be abandoned.

Also when a well is non-productive and the strings of casing are being withdrawn therefrom it often happens that the lifting means for the casing breaks and a string of casing is permitted to fall into the well.

With that heretofore recited in mind, it is the object of the present invention to provide a tool or device which may be employed to serve as a means for catching a string of casing or section of a string of casing in case the same drops when being lowered into or raised from a well.

It is also an object of the invention that the tool or device operate entirely automatically for preventing a string of casing or section thereof from falling into a well.

A further object of the invention is that the tool or device be extremely simple in design and construction, and durable.

Other objects, and objects relating to details of construction, combination and arrangement of parts will hereinafter appear in the detailed description to follow.

The invention is illustrated by way of example in the accompanying drawings, in which:

Figure 1 is a view in elevation of the tool or device embodying the present invention and showing the tool when set and positioned within the lower end of a string of casing, while being lowered into a well, the side walls of the well being shown in cross section.

Figure 2 is a view similar to Figure 1 showing the tool or device when sprung and engaging the wall of the well to hold the string of casing against downward movement.

Figure 3 is a view in side elevation of the tool and showing the same set as seen in Figure 1.

Figure 4 is a view similar to Figure 1 and showing the tool when sprung as seen in Figure 2.

Figures 5 and 6 are transverse sectional views taken substantially on the lines 5—5 and 6—6, respectively, of Figure 3.

Figure 7 is a fragmentary longitudinal sectional view showing the manner of connecting the uppermost section of the tool with the section occurring therebeneath.

Figure 8 is a detail sectional view showing the manner in which the dogs supported upon the lower end of the tool are held in their extended position.

Figure 9 is a view similar to Figure 8 but showing the manner in which the dogs are held positively against inner movement with relation to the tool.

Figure 10 is a perspective view of one of the slips employed upon the tool.

Figure 11 is a detailed sectional view showing the manner in which the slip shown in Figure 10 is releasably held against upward movement.

Figure 12 is a perspective view of one of the dogs shown in Figures 8 and 9.

Figure 13 is a top plan view of the electrical locking means employed in the present tool.

Figure 14 is a view in side elevation of the same.

Referring to the drawings more particu-

larly, in Figures 1 and 2, W indicates generally the walls of a well and the lower end of a string of casing K is being lowered into the well. Upon the lower end of this string 5 of casing there is threaded the usual shoe S which has its lower end beveled as at 9 in the customary manner.

The tool may consist in a stem comprising four sections, namely: A, B, C and D. The 10 uppermost section A is a tubular member or nipple threaded at its upper end as at 10 so that the same may be connected to suitable means for lifting the device from a well. Section B is a tubular member, while sections 15 C and D are solid and cylindrical. The section B may have its one end slightly reduced as at 13 and this reduced portion is threaded as at 14, Figure 7. The section B is connected to the upper end of section C as at 11, 20 and the sections C and D are threaded to each other as at 12', Figure 3. The section A is connected to section B by the means of a collar or band 15, said band being interiorly threaded at each end and adapted to receive the threaded ends of the members A and B. Interposed between the abutting ends of the members A and B is a gasket 16 and a plate 17, the plate 17 being circular as shown and being provided 25 centrally thereof with a suitable recess 18 in which packing 19 may be placed. The plate 17 may be provided with a bore extending through the recess 18 and adapted to receive a shaft or rod 20. A suitable passage or bore is provided in each of the members B, C and D, said passages or bores being in alignment with each other and extending the entire length of said members, as 30 shown to advantage in Figures 3 and 4. 40 The shaft 20 is disposed in these different passages or bores.

The lower end of the member D terminates in an exteriorly threaded portion 26' and above this portion there is provided a 45 plurality of flat faces 21 which are preferably four in number and upwardly divergent. Upon each face 21 there is mounted a dog 22, each dog having an inner flat surface adapted to fit upon a face 21 and having a dove-tail rib formed upon its inner side 50 which is adapted to move in a similar groove 22' formed in the associated face 21. The exterior surface of each member 22 is preferably provided with threads, as shown. 55 Upon the lower end of the member D there is threaded a nose or head 23 which is hollow and preferably of the shape shown. The lower end of the rod 20 extends within the member 23 and has secured thereto a ring 60 25 which is connected to each of the members 22 by a link 26, said links being pivotally connected to the associated member 22 and ring 25 respectively, as illustrated in Figure 2.

65 The member D also carries at a point ad-

jacent its lower end and immediately above the faces 21 a plurality of lugs 27, one of said lugs being specifically shown in Figure 12 of the drawings. As is seen in this figure each lug is in the form of a block having its 70 one end provided with the two divergent outer faces 28 and an intermediate face 29 which is arcuate in cross section. The lower face of each lug is offset to provide a shoulder 30. The lugs are four in number and two 75 of the lugs have formed in their upper face adjacent the outer end thereof a recess 31. Also a side wall of each lug is provided with a groove or recess 32. Each lug is fitted in a suitable opening 33 formed radially of the 80 member D, and a compression spring 34 engages the shoulder 30 of each lug whereby to press the same outwardly. The compression springs 34 are each in the form of a coil spring and positioned in a suitable bore 85 or slot provided in the member D as illustrated to advantage in Figure 8 or 9. In order to limit the outward movement of the lugs 27 a screw 35 is extended through the member D, one for each of the lugs, and said 90 screw having its inner end disposed in the slot 32 of the associated lugs.

At a point adjacent the lower end of the member B there is provided a pair of diametrically opposed offsets or notches 36', 95 each offset being adapted to receive a slip or dog 36. The preferred form of the slips is shown in Figure 10 of the drawings and as seen each dog has its inner face formed with a dove-tail rib 36^a adapted to move in a similar groove 36^b, formed longitudinally of the section C. A pair of springs 37' are provided for each of the dogs 36 and adapted to urge the same upwardly. Also each dog 36 has its outer face roughened as at 38. For 100 each dog there is provided a rod 39 which extends longitudinally of the section C and is disposed in a groove 39^a extending longitudinally of this section. A suitable pin 39^b is used for each of the rods whereby to hold the same against displacement from the associated groove 39^a. The upper end of each rod is formed with a lateral extension 39^c which is adapted to engage in a notch 39^d formed upon the lower end and under 105 face of the associated slip 36, while the lower end of said rod is disposed in the recess or socket 31 of the associated lug 27. Adjacent the upper end of each rod there is positioned a coil spring 39^e which is adapted to press this end of the rod outwardly. With the lugs 27 depressed the rods 39 will engage in the notches 39^d of the slips 36 and hold said slips in the lowered 110 position, as illustrated in Figure 11 of the drawings and against the tension of the springs 37'. Upon the lugs 27 moving outwardly the upper ends of the rods 39 will be forced to move inwardly and thus release the slips 36 so that they may move upwardly un- 115 120 125 130

der the tension of the springs 37'. The purpose of this operation will later be more fully described.

The bore within the member or section D through which the shaft passes is enlarged adjacent its lower end and adapted to receive a sleeve 39'. A coil spring 40 is positioned within the bore and beneath the sleeve, said coil spring encircling the rod 20 and being adapted to urge the sleeve upwardly. The rod 20 is formed with a bulge or enlargement 40' which is adapted to engage the sleeve 39' and limit the movement of said sleeve upon said rod.

15 The member C has its upper end portion formed with an enlarged bore and within this bore there is disposed a coil spring 42 which encircles the rod 20 as shown and which is held against upward movement upon the rod 20 by the means of a collar 43, Figure 4, said collar being secured to the shaft 20 in any preferable manner.

Within the section B there is positioned 25 a plate 44, said plate being secured to the upper end of the section C by the means of screw bolts, or the like, and having a central opening as at 45, through which the stem 20 may pass. Upon this plate there is positioned an electrically operated lock generally indicated by the reference character L which has a catch member 45' adapted to engage a notch in the rod 20, as illustrated in Figure 3 of the drawings, and thereby to hold the rod depressed against the tension of the springs 40 and 42. A suitable dry battery B¹ of one cell or more, if desired, may be placed upon the plate 44 and suitably held by a split sleeve 46 which is formed 30 with a securing flange 47 and secured to the plate 44 by the means of screws or the like as at 48. The plate 44 is also provided with a post 49 which is encircled by a spring 50, and said spring being positioned adjacent the lower end of the post. Upon the spring 50 there is positioned a sleeve 51 and adjacent the upper end of the post there is secured a collar 52 which is insulated from said post, as shown in Figure 14. The collar 52 may be connected through a wire 53 to one binding post 54 of the lock L and the other binding post 55 of the lock L may be connected through a wire 56 to the binding post of the battery B¹ as at 57. The other binding post 58 of the battery B¹ may be grounded as at 58'. As is obvious upon the sleeve 51 engaging the collar 52 an electric current will be established through the lock L for operating the same and thereby to release the rod 20. It also should be mentioned that packing for the rod 20 should be placed at a point below the plate 44 in order to maintain an air tight chamber within section B.

In the use of the present device, assuming that it is intended to lower a string of casing into a well as illustrated in Figure 1, the tool is positioned in the lower end section of the string of casing and the lugs 27 brought to engage beneath the shoe S of the string of casing. This tool may be extended into the lower end of the string of casing; that is, the same may be positioned in the lower end of the first section of casing to be lowered. When positioning the tool the lugs 27 are depressed against the springs 34 and the rods 39 are arranged so that they hold the slips 36 in their depressed position and thereby permitting the tool to be inserted into the casing K without difficulty. Upon the tool reaching the position shown in Figure 1, the lugs 27 are released whereupon the rods 39 will be released at their upper ends so that the slips 36 may move upwardly against the tension of the springs 37' and these slips will move to the position illustrated in Figures 3 and 4. When in this position the slips retain the tool against downward movement. The string of casing may now be lowered and should the lowering means break and the string of casing begin to fall, the inertia of the sleeve 51, accentuated by the tendency of the spring 50 to expand, would cause the sleeve 51 to move upwardly, engage the collar 52 and thereby establish an electric current for operating the lock L and in this way releasing the rod 20. Upon the rod 20 being released the same will move upwardly and carry therewith the dogs 22 which will engage with the wall of the well as illustrated in Figure 2 and prevent further downward movement of the string of casing. Also during the upward movement of the rod 20 the sleeve 39' is permitted to proceed upwardly and move so that the same is disposed at the rear of the lugs 27 and thereby prevent further inward movement of said lugs. The lugs will then be positioned, as shown in Figure 2, and engage the shoe S. The string of casing will be held within the well and suitable means may be engaged with the upper end thereof whereby to raise the same. Upon slightly raising the casing then a suitable tool may be inserted in the string of casing so that the rod 20 may be depressed to again return the dogs 22 to their position shown in Figures 1 and 3 and now the continuing of the lowering of the casing may be proceeded with. Upon the casing being entirely lowered the head 23 will engage with the bottom of the well, and due to the fact, that the lugs 27 may easily be depressed, the pressure of the casing shoe S against these lugs will depress the same and permit the tool to be shoved upwardly into the casing. The threads or roughened exterior surface of the slips 36 will not in-

terfere with the upward movement of the tool. These slips in fact serve only for the purpose to prevent downward movement of the tool. This tool will in this way be 5 grounded upwardly and then a suitable means may be lowered into the casing and the tool withdrawn.

Assuming that it is desired to raise a string of casing from the well, the tool may 10 be inserted in the lower end of a casing in order to prevent loss of the same, that is, to prevent dropping of the casing in case the lifting means should break. The string of casing to be lifted should be slightly raised 15 and then the tool lowered to the lower end of this string of casing. The lugs 27 should be depressed so that the slips 36 will likewise be depressed and in this way permit easy lowering of the tool. Upon the lugs 27 20 reaching the lower end of the casing the same will distend and simultaneously therewith the rods 39 will be released to permit the slips 36 to move upwardly and thus engage the side of the casing. The tool will 25 be held against further downward movement by the slips 36. Any suitable means may now be attached to the string of casing and the same may be lifted from the well. Should these means break and permit the 30 casing to drop the lock L will be again operated to trip the tool and in this way the dogs 22 will be brought into engagement with the sides of the well and hold the string of casing against further downward movement. 35 In case that another string of casing is within the well the different walls of this string of casing will be engaged by the dogs 22 in the same manner as these dogs engage the walls of the well to sustain the string of casing being withdrawn.

While I have shown and described the preferred form of my invention, I wish it to be understood that I am aware of the fact, that the construction, combination and arrangement of parts may be changed by those skilled in the art without departing from the spirit of the invention, as indicated by the appended claims.

I claim:

50 1. In combination, a casing adapted to be lowered into a well, a tool adapted to be inserted in the lower end of said casing, and said tool being adapted to operate for engaging the walls of the well and supporting said casing against further downward movement upon said casing being allowed to freely drop into the well a predetermined distance.

60 2. In combination, a casing adapted to be lowered into a well, a tool adapted to be inserted in the lower end of said casing, distensible dogs carried by said tool, and means for operating said dogs to grip the sides of the well and support said casing against

further downward movement, said means 65 being adapted to be set into operation upon the casing being permitted to drop a predetermined distance within the well.

3. In combination, a casing adapted to be lowered into a well, a tool adapted to be 70 inserted within the lower end of the casing, means carried by the tool adapted to prevent further downward movement of the same, and means extending from the tool adapted to engage the sides of the well into 75 which the casing is being lowered and support the casing against downward movement, said means being operable automatically upon the casing freely dropping within in said well a predetermined distance. 80

4. In combination, a casing adapted to be lowered into a well, a tool adapted to be inserted within the lower end of the casing, means carried by the tool adapted to prevent further downward movement of the 85 same, means extending from the tool adapted to engage the sides of the well into which the casing is being lowered and support the casing against downward movement, said means being operable automatically upon 90 the casing freely dropping within said well a predetermined distance, and means carried by the tool adapted to engage the bottom of the well previous to the operation of the dogs carried thereby and cause the 95 tool to move upwardly within the casing and permit the associated casing to seat in the bottom of the well.

5. A tool of the character described, comprising a stem, a rounded head, a plurality 100 of flat faces formed upon the stem adjacent the head and divergent upwardly with respect to said head, a dog slideable upon each face, a rod extending longitudinally of the stem and centrally thereof, connecting means between the dogs and rod whereby 105 said dogs may be moved longitudinally of said divergent faces, means whereby said rod may be pressed upwardly to move the dogs to their uppermost position, and means for releasably holding the stem in a depressed position to hold the dogs in their lowermost position. 110

6. A tool of the character described, comprising a stem, a rounded head, a plurality 115 of flat faces formed upon the stem adjacent the head and divergent upwardly with respect to said, a dog slideable upon each face, a rod extending longitudinally of the stem and centrally thereof, connecting means between the dogs and rod whereby said dogs may be moved longitudinally of said divergent faces, spring means for pressing the rod upwardly to bring the dogs to their uppermost position, and releasable locking 120 means adapted to hold the rod in a depressed position for maintaining the dogs in their lowermost position. 125

7. A tool of the character described, comprising a stem, a rounded head, a plurality of flat faces formed upon the stem adjacent the head and divergent upwardly with respect to said head, a dog slideable upon each face, a rod extending longitudinally of the stem and centrally thereof, connecting means between the dogs and rod whereby said dogs may be moved longitudinally of

5 said divergent faces, spring means for pressing the rod upwardly to bring the dogs to their uppermost position, and electrical lock means adapted to operate upon the tool being permitted to drop downwardly 10

15 a predetermined degree whereby to release the rod and permit the dogs to move to their uppermost position for the purpose described.

8. A tool of the character described, comprising a stem terminating at its lower end in a rounded head, a plurality of flat divergent faces formed adjacent the head and said faces divergent upwardly, a dog movable upon each face, a rod extending longitudinally of the stem and centrally thereof, connecting means between each dog and rod whereby the dogs may be moved to either a lowered or raised position, a plurality of depressible lugs above said divergent faces and carried by the stem, means for forcing the rod upwardly to bring the dogs to their uppermost position, means for releasably locking the rod in a lowered position

10 to bring the dogs to their lowered position, and means whereby upon the rod being released the lugs above said dogs will be held against depression. 35

9. A tool of the character described, comprising a stem terminating at its lower end in a rounded head, a plurality of flat divergent faces formed adjacent the head and said faces divergent upwardly, a dog movable upon each face, a rod extending longitudinally of the stem and centrally thereof, connecting means between each dog and

40 rod whereby the dogs may be moved to either a lowered or raised position, a plurality of depressible lugs above said divergent faces and carried by the stem, means for forcing the rod upwardly to bring the

45 dogs to their uppermost position, means for releasably locking the rod in a lowered position to bring the dogs to their lowered position, means whereby upon the rod being released the lugs above said dogs will be held against depression, a plurality of slips

50 above the lugs and carried upon said stem, said slips being depressible downwardly and when in a depressed position to be within the outer periphery of the stem, and means whereby the slips may be held in depressed position, said means being releasable upon the dogs being moved to their uppermost position. 55

JAY KELLY LIVINGSTON.
